REAMING AND HONING DEVICE

Fred W. Steenbock, Sylvan Grove, and William P.
Naegele, Lucas, Kans.

Application January 14, 1944, Serial No. 518,274

1 Claim. (Cl. 51—194)

The present invention relates to improvements in reaming or honing tools, and aims to provide a novel rotary type of tool of this character adapted to use sheets of abrasive material such as emery cloth and the like for carrying out the cutting or abrading function.

Accordingly a primary object of the invention is to devise a novel construction of tool of this type in which the sheets of abrasive material are so utilized as to promote not only ready and convenient renewal or replacement of said material as required but also to feed any required amount of the material to the exterior of the tool whereby the size or diameter of the tool may be suitably varied to meet different operating requirements.

A further object of the invention is to provide a practical and efficient construction in which improved means is provided for securing the inner edge of the sheet of abrasive material to the axis of the tool, said means being adapted for easy and ready adjustment as well as for securely clamping the sheet in place.

It is further sought to provide a construction in which the metallic parts, such as the principal sleeve element may be kept as small as practicable, or made of light and relatively thin stock in order to adapt the tool for light duty and for working in close quarters.

Another detail of the improvement comprises use of different grades of abrasive material, in which operation a supplemental sheet of such material may be readily mounted in operative position on the tool by being simply inserted so as to be caught and held by engagement with the free edge of the sheet of material already in place on the tool.

With the foregoing general objects in view the invention will now be described by reference to the accompanying drawing illustrating one practical form of the tool which we have devised for embodying our features of improvement, after which those features and combinations regarded by us as novel and patentable will be particularly set forth and claimed.

In the drawing—

Figure 1 is a perspective view of a tool constructed in accordance with our invention;

Figure 2 is a longitudinal sectional view of the same (on a somewhat larger scale); and

Figures 3, 4 and 5 are transverse sectional views, representing sections taken on the lines 3—3, 4—4 and 5—5, respectively, of Figure 2, but with Figure 5 illustrating the application

of a supplemental sheet of abrasive material to the exterior of the tool.

Referring now to the drawing in more detail, this illustrates our improved tool construction as comprising a central axis in the form of a shaft 8, having a shank or drive end portion 10, which is provided with a fixed abutment or collar element 12. This collar is reduced on one face to form an annular shoulder 14 of appropriate diameter for fitting within one end of a metallic sleeve 15, which is formed with a longitudinal and somewhat angular slot 16 for allowing the passage of a web or sheet of abrasive material, such as emery cloth 18, as clearly illustrated in Figure 3. The other end of the sleeve 15 also fits over a similar shoulder 20 forming part of a movable collar element 22 which is backed up by a clamping nut 23 also mounted on the corresponding end of the shaft 10, which is threaded (as indicated at 24) for the operation of said nut in holding the collar 22 in place as required for maintaining the sleeve 15 in securely clamped relation between the collars 12 and 22 when the tool is put in operation.

For securely clamping the inner end of the sheet of emery cloth or other abrasive material, the shaft 10 is formed with a longitudinal groove or recess 26 into which said end of the sheet is tucked and then engaged by a clamping or retaining rod 28, one end of which is removably inserted into an opening or recess 30 within the fixed collar element 12, while the opposite end of said rod is received within a flaring cup opening 32 provided in one face of a nut 34 also mounted on the thread 24, whereby as the nut 34 is screwed up on the shaft the rod 28 is crowded down into the groove 26 and thus into firmly clamping relation to the inner end of the emery sheet 18, as clearly represented in Figure 2 of the drawing.

When the sheet of emery cloth is thus properly secured to the shaft as just described, the cloth is then wound around the shaft, reel fashion, and the sleeve 15 is pushed endwise over the roll of cloth in telescoping relation therewith, but leaving the outer or free end of the sheet projecting out through the longitudinal slot 16. Through this slot 16 the cloth is then pulled in order to bring a sufficient quantity or number of turns of the cloth to the outside of the sleeve. After a proper amount of the material has been pulled into place outside the sleeve 15, the sleeve is then clamped tightly between the end collars by screwing the nut 23 in place against the collar 22, as shown.

The tool may then be operated as a reamer or honing device in the usual manner, by rotation in the direction of the arrow in Figure 3, which operation is carried out without disturbing the wound relation of the cloth or abrasive material 18, other than to maintain it in its highly wound relation upon the shaft and around the outside of the sleeve. In case it should be desired to change the outside diameter of the device, for either increasing or diminishing the size of same, it is apparent that this may be readily accomplished by simply readjusting the roll to vary the number of turns of the cloth material on the outside of the sleeve 15, in a very convenient manner.

For facilitating the insertion of the tool into operative position, it is preferred to taper one end of the sleeve 15 slightly, as indicated in Figures 1 and 2; and for further promoting such ready insertion of the tool, one corner of the projecting end of the sheet 18 may be cut or torn away, as indicated at 18' in Figure 1.

Another advantage which characterizes such application of the sheet of abrasive material is the fact that this facilitates the use of supplemental sheets of abrasive material, such as indicated at 36 in Figure 5, inasmuch as such supplemental sheets may be held securely in place by simply lapping one edge of it either above or below the exposed end of the first sheet 18 and then winding up the roll of material until the desired amount of the sheet 36 is left outside the sleeve 15 for arriving at a proper diameter of the tool. This feature is of importance where a finer grade of abrading cloth is necessary for finishing purposes, and which operation may thus be carried out with the same tool, with the mere application of the supplemental sheet of the required grade to the outside of the first sheet and then winding up the two sheets to the required extent.

It will thus be apparent that we have devised a practical and highly efficient type of tool for the carrying out of various abrading operations, such as in reaming or honing and the like; and besides the various advantages described in the foregoing, it is also obvious that fresh portions of the abrasive cloth material may be fed out as required, through the slot 16 of the sleeve 15, and also that an entirely new sheet of the material may be mounted in place to take the place of a worn-out sheet by manipulation of the clamping means 28 and 34, in a quick and convenient manner, as will be readily understood from the foregoing description.

While we have illustrated and described what is now regarded as the most effective means for practice and embodiment of our invention, we desire to be understood as reserving the right to make all such changes or modifications as may fairly be deemed to fall within the scope of the invention as defined by the appended claim.

We claim:

An abrading or honing tool comprising a central shaft having a drive end, a fixed collar on said drive end portion of the shaft, a removable sleeve for enclosing a sheet of abrasive material in coiled relation to said shaft and formed with a longitudinal slot for allowing passage of the abrasive material to the exterior of said sleeve, said shaft having a longitudinal groove for receiving the inner edge of said material, a removable rod for clamping the material in said groove, a movable collar on said shaft for engagement with one end of said sleeve, and a pair of nuts threaded on said shaft for respectively holding said rod in clamping position and maintaining said sleeve in clamped relation between said fixed and movable collars.
